15 Claims. (Cl. 38—59)

The present invention relates to ironing machines, more particularly of the type comprising an ironing roller cooperating with a heating pad and a guide or feeding board for the introduction of the material to be ironed between said pad and roller.

The invention has for its main object the provision of improved operating and control means to operate said roller to and retract it from its operative or engaged position with the heating pad and to control the rotation of the roller by means of a single electric motor in cooperation with selective coupling means for the roller displacing and rotating mechanisms, respectively.

A more specific object of the invention is to simplify the operation of an ironing machine of the type referred to by the control of substantially all the movements or operations necessary for the carrying out of an ironing operation, including the engagement of the ironing roller with the heating pad, rotation of the roller for the carrying out of an ironing operation, and retraction from said pad both in the operating and rest position of the roller, by the mere change of the direction of rotation of a reversible electric driving motor.

Yet another object of the invention is the provision of improved operating and control mechanism for ironing machines of the type referred to, which is both simple in design and construction, as well as efficient and reliable in operation, to enable its ready and safe use by the average person or operator substantially without the exercise of any special skill or operating experience.

The invention, both as to the foregoing and ancillary objects as well as novel aspects thereof, will be better understood from the following detailed description, taken in conjunction with the accompanying drawings forming part of this specification and in which:

FIG. 1 is a general perspective view of an ironing machine according to the invention;

FIG. 2 is a perspective view of the drive and operating mechanism embodied in the machine of FIG. 1 and being constructed in accordance with the principles of the invention;

FIG. 3 is a partial perspective sectional view taken on line III—III of FIG. 2;

FIG. 4 is a cross-section taken on line IV—IV of FIG. 1;

FIG. 5 is a perspective view of a part of FIG. 2;

FIG. 6 is a longitudinal sectional view of an alternative selective coupling mechanism forming part of the invention;

FIG. 7 is a partial view in developed form of a component of FIG. 6;

FIG. 8 is a partial view in developed form of another component part of FIG. 6; and

FIG. 9 is a wiring diagram of the electrical control circuits of the ironing machine of the invention.

Like reference numerals denote like parts throughout the different views of the drawings.

With the foregoing objects in view, the invention, according to one aspect thereof, involves the provision, in connection with an ironing machine of the type referred to, of a rotatable or otherwise movably supported guide or feeding board operable between a normal position and at least one control position, of first drive and operating

mechanism including a cam and follower motion-transmitting device, to operate the rotatably supported ironing roller into engagement with and to retract it from the stationary feeding pad, respectively, during alternate half-turns of a full revolution of said device, and second drive and operating mechanism to rotate said roller, for the carrying out of an ironing operation. In order to selectively operate the roller displacing and rotating mechanisms, there is provided by the invention multiple selective coupling means connecting said mechanisms with a reversible driving motor, to operate either mechanism in dependence upon the sense of rotation of said motor. Finally, the invention contemplates the provision of electric circuit and control means for said motor being operably connected with both the feeding board and the ironing roller displacing means, whereby to start the motor in a first direction and to operate the ironing roller into engagement with its heating pad, and to subsequently arrest and re-start the motor in the opposite direction, to rotate said roller, by the simple operation of said board from its normal position to and release from its control position, respectively.

In carrying into effect the invention, the pins or the like switch actuating elements for effecting the starting of the motor are preferably controlled by the feeding board, while the switch actuating elements for stopping and reversing the motor are controlled by the ironing roller displacing means, whereby to result in a most simple and efficient design as well as operation of the control mechanism.

Auxiliary control means may be provided to arrest the motor and, in turn, the ironing operation, in the operative position of the ironing roller and to operate the roller displacing means in the rest position of the motor, as described and explained in greater detail in the following in reference to the drawings.

The multiple selective coupling mechanism, responsive to the direction of rotation of the driving motor or input coupling member, respectively, may be of any suitable construction, such as in the form of a pair of free-wheeling or scrag-type one-way coupling units having a common input member and a pair of output members, or in the form of a special axially displaceable coupling member driven by the motor through a spiral gear transmission and cooperating with a pair of coaxial output members, as shown by the drawings and described in greater detail hereinafter.

Referring more particularly to FIG. 1, the numeral 1, denotes an ironing or mangle roller being rotatably mounted upon the end of a pair of parallel swiveling arms 2 and 3, said arms having their opposite ends secured to a hollow shaft or tube 5 rotatably mounted upon the frame 4 of the machine, to form a swiveling support for said roller. Further mounted upon the frame 4 and within the housing 6 is the support or casing 7 of the drive mechanism for the roller 1, said housing having in turn affixed thereto a further support 8 carrying a curved heating pad or cradle 9, the latter being equipped in known manner with electrical heating coils (not shown) for cooperation with the ironing roller 1.

Rotatably connected to the support 8 about pins or screws 11, is a guide or feeding board 10 being resiliently urged to a rest or normal position I, FIG. 9, by a spring or the like 12, FIG. 4.

Mounted upon or within the support 8 may be a thermometer 13 and a knob or the like control member 14 for adjusting the ironing temperature, in a manner well known and understood.

Mounted within the housing 6 is a reversible alternating current motor 15, FIG. 2, whose direction of rotation may be controlled by polarity reversal of an auxiliary phase winding b, FIG. 9, fed through a capacitor, in a

manner as will become further apparent as the description proceeds. Fixedly mounted upon the shaft 16 of the motor 15 is a driving pinion 17 which is in meshing engagement with a toothed collar or externally threaded ring gear 18. Additional reduction gearing (not shown) may be interposed between the pinion 17 and gear 18, to reduce the relatively high motor speed to an appropriate speed for the operation of the swiveling arms 2 and 3, to effect engagement and disengagement, respectively, of the roller 1 and pad 9.

The ring gear 18 is coaxial with a shaft 19 mounted in the casing 7 of the drive mechanism, said shaft rotatably supporting a further pinion 20, on the one hand, and a sleeve 21, on the other hand. Pinion 20 is connected, in the example of FIG. 2, with the roller guide 23, FIG. 3, of a first uni-directional or one-way coupling unit and sleeve 21 is connected with the roller guide 22 of a further one-way coupling unit, said guides being provided in a known manner with wedge-shaped peripheral recesses in which are mounted coupling rollers 25 and 24, respectively. The guides 22 and 23 and associated coupling rollers are disposed within the gear 18 on the opposite sides of a central spacing disk 26 and retained by covering disks or washers 27 secured to cylindrical extensions on the opposite sides of said gear. The recesses of the guides 22 and 23 are oriented in such a manner that, with the gear 18 rotating in one direction, the rollers 24 are pressed against the inside wall of the gear 18, to effect driving connection with the guide 22, while the rollers 25 are disengaged from the gear 18, and that, with the gear 18 rotating in the opposite direction, the rollers 25 effect coupling between the guide 23 and gear 18, while the rollers 24 are disengaged from said gear.

The pinion 20 is in driving connection, by way on intermediate gears 28, 29, with a further gear 31 secured to a shaft 30 which is rotatably supported within the tube 5, said shaft serving to rotate the ironing roller 1 through a first pulley 32 connected therewith, a second pulley 33 upon said roller and a belt 34 operably connecting said pulleys and being enclosed by the swiveling arm 2, in the example illustrated.

Secured to the sleeve 21 driven by the roller guide 22 is an eccentric 35 which cooperates with a follower roller 37 rotatively mounted upon the pivot pin 37 of a knee lever or knuckle joint 38. The latter comprises a first element in the form of a pair of flat bars 39 and a forked element 40 connected, by means of a screw 41 and nut 42, FIG. 4, to a further forked element 43, a compression spring 44 being interposed between the elements 40 and 43. Element 43 is linked, through a bolt 45, to the lower end of an actuating arm or lever 46 having its upper end fixedly secured to the tube 5. Connected to the support 7 are a pair of supporting plates or brackets 48 provided with longitudinal slots 47 being slidably engaged by a bolt 49 connecting the bars 39. Mounted upon the bolt 49 and between the bars 39 is a further roller 50 which cooperates with an eccentric 51 being secured to a shaft 52 rotatively supported by the frame 4. Connected to both ends of the shaft 52 are a pair of levers or handle bars 53, FIG. 1, while the shaft is provided with a stop lever 54 arranged to cooperate with a stationary stop or adjusting screw 55 mounted in the housing 6.

The knee lever 38 is fitted with a tension spring 56 arranged with its opposite ends engaging a bore in the bracket 48, on the one hand, and a bore in the lever 46, on the other hand, whereby to continuously urge the roller 37 into resilient engagement with the eccentric 35.

Rotation of the shaft 52 carrying the eccentric 51 causes displacement of the bolt 49 within the slots 47 for effecting a manual control of the position of roller 1, adjustment of the tension of the biasing spring 44 being effected by means of the set screw 55, as pointed out hereinbefore. Variation of the tension of the spring 44 results in a control of the operating pressure between the roller 1 and heating pad 9.

In place of the free-wheeling or wedge and roller type uni-directional clutch units of FIG. 2, connecting the drive pinion 17 with the swiveling and rotating mechanism of the roller 1, respectively, any other type of one-way couplings may be utilized for the purpose of the invention, such, for instance, a clutch utilizing a winding and unwinding coil spring connecting a pair of coaxial input and output members, or a direction-responsive selective gear-shift mechanism described in the following 10 and shown by FIG. 6.

Referring to the latter, the numerals 57 and 58 represent a pair of set rings or collars secured to the shaft 19 in spaced relation to one another and between which is disposed the directional gear-shift type coupling or assembly 59. The previously described eccentric 35 is fixedly connected with a coupling sleeve 60 one front surface of which is fitted with coupling teeth 61 or the like. Similarly, one front surface of the hub of the driving gear or pinion 62, also described hereinbefore, is fitted with coupling teeth 63. Disposed between the coupling sleeve 60 and the hub of the pinion 62 and mounted upon the shaft 19 are a sleeve 64 and a pair of guard plates or washers 65 and 66 at the opposite ends of said sleeve. Rotatably supported by the sleeve 64 and in axially slidably relation thereto is a coupling sleeve 69 having a flange 70. Secured to the coupling sleeve 69 is a spiral gear 71 having a hub 72 wherein are mounted a pair of tap screws 73 secured by means of nuts 74. Gear 71 meshes with a spiral driving pinion 75 being secured to the motor shaft 16 and replacing the gear 17 of FIG. 2. Sleeve 69 is furthermore formed at its opposite ends with coupling teeth 67 and 68, FIG. 7, adapted to cooperate, respectively, with the teeth 61 and 63.

The central portions of the coupling sleeve 69 and of the sleeve 64 are formed with registering slots 76 and 77, respectively, slot 77 having an extension forming an angle α , FIG. 8, with its main portion registering with the slot 76. The slots 76 and 77 form an angle with the axis of the sleeves 64 and 69 for the purpose as described hereafter. Interposed between the flange 70 of the coupling sleeve 69 and the hub 72 is a cup spring 78, to maintain the sleeve in resilient engagement with the output coupling members, in the manner further understood from the following.

The operation of the invention as exemplified by FIG. 2 is described in the following in further reference to FIG. 9.

To begin with, the desired ironing temperature of the pad 9 is adjusted with the aid of the thermometer 13 and by rotation of the knob 14.

Before starting the ironing operation, it is necessary to rotate the roller 1 into operative pressure engagement with the pad 9 by initiating the swiveling movement of the supporting arms 2 and 3. This is achieved by depressing the guide board 10 from the normal rest position I to a position III, FIG. 9. As a consequence, the contacts 83 and 84 of the switches 81 and 82 are opened by actuation of the tripping pins 79 and 80, while at the same time closing the contacts 85 and 86 of the same switches. In this position, the contacts 85 bridge the contacts 87 of the switch 88 which has a contact arm normally held in open position by the tripping pin 89 being engaged by the switch arm 90 secured to and extending from the tube or shaft 5.

As a consequence, operation of the board 10 from the position I to the position III results in the establishment of a first electric operating circuit (A) being traced as follows: Terminal P of the alternating current source—lead 91—terminal 92—lead 93—contacts 85—terminal 94—lead 95—motor winding a—motor winding c—lead 96—terminal 97—lead 98—contacts 86—terminal 99—lead 100—capacitor 101—auxiliary motor winding c—lead 96—terminal O of the current source.

As a result of the closing of the circuit (A), the motor 15 is started in one direction, that is, as shown by the 75 arrow R, FIG. 2, whereby to cause the pinion 17 to rotate

the ring gear 18 in the direction of the arrow D. As a consequence, the rollers 24 effect driving connection between the gear 18 and the sleeve 21 by way of the roller guide 22, whereby to rotate the eccentric 35 in the direction of the arrow D. The eccentric 35 cooperating with the roller 37 of the knee lever 38 causes the ironing roller 1 supported by the swiveling arms 2 and 3 to be operated towards and into engagement with the pad 9, the knee lever 38 being operated during this movement from a normally angular to a stretched position against the action of the spring 56. As a consequence, the switch arm 90 is disengaged from the tripping pin 89 at the beginning of the swiveling movement of the roller 1, whereby to close the contacts 87. The feeding board 10 is then released and returned to its normal position I by the action of the spring 12, whereby to re-close the contacts 83 and 84. As a consequence, there is established an intermediate operating or holding circuit (B) being traced as follows: Terminal P of the current source—lead 91—contacts 87—lead 102—terminal 103—contacts 104—lead 105—terminal 106—motor winding a—motor winding c—lead 96—terminal 107—lead 108—contacts 109 of switch 110—lead 111—contacts 84 of switch 82—lead 100—capacitor 101—auxiliary motor winding b—motor winding c—lead 96—terminal O of the current source.

During continued rotation of the arms 2 and 3 and switch arm 90, actuation of the tripping pins 112 and 113 of the switches 110 and 114 cause the circuit (B) to be interrupted and the motor 16 to be stopped temporarily. After the roller 1 has reached its final operating position of engagement with the pad 9, contacts 115 and 116 of the switches 110 and 114 are closed, whereby to reverse the polarity of one phase winding of the motor and to restart the same in the opposite direction, that is, as shown by the arrow V in FIG. 2, by the establishment of a reverse operating circuit (C) being traced as follows: Terminal P of the current source—lead 91—contacts 87—lead 102—contacts 116—lead 117—contacts 83—lead 95—terminal 118—lead 119—contacts 115—terminal 120—lead 111—contacts 84—lead 100—capacitor 101—auxiliary winding b—winding c—lead 96—terminal O of the current source.

Upon re-starting of the motor in the reverse direction, the pinion 17 upon the motor shaft 16 drives the gear 18 in the direction indicated by the arrow E. As a consequence, the rollers 25 effect driving connection between the gear 18 and the roller guide 23 connected with the pinion 20, while the rollers 24 are disengaged from the gear 18. Pinion 20, in turn, causes rotation of the shaft 30 by way of the intermediate gears 28, 29 and 31. Rotation of shaft 30 is transmitted to the ironing roller 1 by means of the pulleys 32, 33 and belt 31. The machine is now ready for operation by inserting of goods or sheets to be ironed between the roller 1 and pad 9 with the aid of the guide or feeding board 10.

The roller 1 may be stopped temporarily, or the ironing operation interrupted by opening the circuit (C), by depressing the board 10 to an intermediate position II and opening of the switch contacts 83. Upon release of the board 10, the spring 12 will return the same to the normal position I, whereby to re-close the contacts 83 and to re-start the motor and roller 1.

In order to return the ironing roller from its operative or engaged position with the pad 9 to its inoperative or retracted position, the board 10 is operated to the position III, whereby at first to open the contacts 83 and to arrest the motor and to subsequently close the contacts 85 and 86 and to re-start the motor in the direction of the arrow R by the closing of operating circuit (A). As a consequence, the pinion 17 drives the gear 18 in the direction of the arrow D and the rollers 24 effect driving connection between the guide 22 and the gear 18. At the same time, the driving connection between the guide 23 and gear 18 is interrupted by disengagement of the rollers 25, in a manner well known in connection with sprag or

wedge and roller type unidirectional clutches of this type.

After the eccentric 35 has completed one half turn to release the knee lever 38 from the influence of the spring 56, the switch arm 90 actuates the tripping pin 89 of the switch 83, thus interrupting the current supply and effecting stoppage of the motor 15 by the opening of contacts 87.

In the following will be described the operation of the selective directional coupling 59 of FIG. 6 which may replace the free-wheeling uni-directional clutch mechanism of FIG. 2.

In the starting position of the machine, that is, with the pad 9 being disengaged from the ironing roller 1, operation of the roller to its operative position or engagement with the pad is again initiated by operating the board 10 from its normal position I to its position III, to start rotation of the motor in the direction of the arrow R, FIG. 6, in the manner described hereinbefore. As a consequence, the spiral pinion 75 upon the motor shaft 16 drives the spiral gear 71 and coupling sleeve 69. By virtue of the action of the spiral gear teeth, the gear 71 and coupling sleeve 69 are displaced axially (arrow F) until the coupling teeth 61 engage the teeth 67, to establish driving connection with the sleeve 60 and, in turn, with the eccentric 35. The extent of the axial displacement of the sleeve 69 and gear 71 is limited by the pins or screws 73 engaging the slots 76 and 77.

As a consequence, the eccentric 35 cooperating with the roller 37 at the pivot point of the knee lever 38, FIG. 2, causes the swiveling arms 2 and 3 and, in turn, the roller 1 to be operated into engagement with the pad 9 by operation of the knee lever 38 from its bent to its stretched position against the action of the spring 56, in substantially the same manner as described hereinbefore in reference to FIG. 2. Upon reaching the operative position of the roller 1, the motor is at first disconnected and restarted in the opposite direction (arrow V) by the operation of the switches 110 and 114, whereby to rotate and displace the gear 71 axially in the direction of the arrow G due to the action of the spiral gear teeth and to effect engagement between the coupling teeth or sprockets 68 and 63, being oriented in a direction opposite to the coupling teeth 61, 67, or driving connection between the sleeve 69 and pinion 62, respectively. This, in turn, results in the rotation of the roller 1 by way of gears 28, 29, 31, shaft 30, pulley 32, belt 34 and pulley 33, in substantially the same manner as described and understood from the foregoing. Temporary stoppage of the ironing roller in the operative position and return to its inoperative position may again be effected by the operation of the board 10 to positions II and III, respectively, in the manner described in reference to FIG. 2.

During rotation of the eccentric 35, its contact with the follower 37 is maintained by the spring 56, whereby the knee lever assumes an angular position after rotation of the eccentric through an angle of 180° or the distance between the axis 19 from the bolt 36 is at a minimum. During this operation of the eccentric, the swiveling arms 2 and 3 are rotated by the spring 56 such as to disengage the roller 1 from the pad 9. During the retraction of the roller, the eccentric 35 is under the influence of the spring 56 and is subject to a torque causing an advance of the eccentric and, in turn, a non-uniform swiveling movement of the arms 2 and 3 and the roller 1.

The screws 73 act to limit the rotation of the eccentric 35 by engaging the slots 76 and 77 being arranged at such an angle so as to provide a controlling or counter force or breaking action on the movement of the eccentric. This function is assisted by the spring 78 interposed between the flange 70 and hub 72.

After the eccentric 35 has completed a half turn, the roller 1 reaches its inoperative position, whereupon the switch arm 90 actuates the tripping pins 89 of the switch 83, whereby to open the contacts 87 and to stop the machine in the manner described.

In the foregoing, the invention has been described in reference to specific illustrative devices and mechanisms. It will be evident, however, that variations and modifications, as well as the substitution of equivalent parts or devices for those shown herein for illustration, may be made without departing from the broader scope and spirit of the invention as defined by the appended claims. The specification and drawings are accordingly to be regarded in an illustrative rather than in a restricted sense.

I claim:

1. In an ironing machine, a frame, a hollow shaft journaled in said frame, a heating pad mounted upon said frame, an ironing roller for cooperation with said pad, a guide board for feeding ironing material to said pad and roller, said board being mounted in relative rotative relation to said frame and operable between a normal position and at least one control position, a swiveling support including means to rotatively support said roller and being connected to said shaft, first drive mechanism including a cam and follower device, to rotate said shaft and to operate said roller into pressure engagement with and to retract it from said pad, respectively, during alternate half-turns of a full revolution of said device, second drive mechanism including a further shaft journaled within said hollow shaft, to rotate said roller, a reversible electric motor, multiple selective coupling means connecting said motor with said first and second mechanisms and comprising an input coupling member driven by said motor, a pair of output coupling members each operably connected with one of said mechanisms, intermediate coupling means interposed between said input coupling member and each of said output coupling members and being effective in establishing coupling connection of said input member with either of said output members in dependence upon the direction of revolution of said input member, respectively, and electric circuit and control means for said motor operably connected with said board and said support, to start said motor in a first direction and to operate said roller into pressure engagement with said pad by said first mechanism, and to subsequently arrest and re-start said motor in the opposite direction, to rotate said roller by said second mechanism, by operation of said board from its normal position to and release from said control position.

2. In an ironing machine as claimed in claim 1, said board being provided with means to resiliently urge the same into said normal position.

3. In an ironing machine as claimed in claim 1, said board being provided with means to resiliently urge the same into said normal position, and additional control means to interrupt the motor operating circuit during the reverse motor operation by a further control position of said board intermediate said normal and first control positions.

4. In an ironing machine as claimed in claim 1, said board being provided with means to resiliently urge the same into said normal position and said circuit and control means being designed to start said motor by the establishment of a first operating circuit in a first direction upon operation of said board from its normal position to said control position, to continue rotation of said motor in said first direction upon initial displacement of said swiveling support and release of said board by the establishment of a second operating circuit, and to stop and re-start said motor in the opposite direction by the establishment of a third operating circuit upon said roller reaching its engaged position with said pad.

5. In an ironing machine as claimed in claim 4, including additional control means to temporarily interrupt said third operating circuit in a second control position of said board intermediate said normal and first control positions thereof.

6. In an ironing machine as claimed in claim 1, said input member having an internal cylindrical surface and said coupling organs being comprised of a pair of roller

guides each connected to one of said mechanisms, said guides arranged within and coaxial with said member and having wedge-shaped peripheral recesses adapted to receive coupling rollers, the recesses of said guides being relatively oriented, to cause selective coupling engagement of said input member with either of said guides in dependence upon the sense of rotation of said input member.

7. In an ironing machine as claimed in claim 1, said input member being comprised of a rotatively supported and axially displaceable sleeve driven by said motor through a spiral gear transmission, said sleeve having its opposite front surfaces provided with coupling teeth and said output members having front surfaces provided with coupling teeth for cooperation with the teeth of said sleeve, whereby to effect selective coupling engagement between said sleeve with either of said output members by rotation and axial displacement of said sleeve in dependence upon the sense of rotation of said motor.

8. In an ironing machine as claimed in claim 7, including stop means to limit the axial displacement of said sleeve.

9. In an ironing machine as claimed in claim 7, said sleeve being mounted upon a cylindrical support and both said sleeve and support being provided with at least one pair of registering slots including an angle less than 90° with the cylinder axis, said transmission comprised of a spiral pinion, driven by said motor and a spiral gear having a hub mounted upon said sleeve, and a radial pin extending from said hub and engaging said slots, to limit the axial displacement of said sleeve upon said member.

10. In an ironing machine as claimed in claim 1, said first mechanism including a knee lever comprised of a first element pivoted at one end, a second element having an end linked to said hollow shaft, and a pivot pin connecting said first and second elements, and said follower consisting of a cylindrical roller mounted upon said pin, and spring means to maintain said cam in continuous engagement with said roller.

11. In an ironing machine as claimed in claim 10, said second element of said lever consisting of two parts resiliently connected with one another, and means to adjust the resilient connecting force between said parts.

12. In an ironing machine, a frame, a shaft journaled in said frame, a heating pad mounted upon said frame, an ironing roller for cooperation with said pad, a guide board for feeding ironing material to said pad and roller, said board being mounted in relative rotative relation to said frame and operable between a normal and at least one control position, a swiveling support connected to said shaft and including means to rotatively support said roller, first drive and operating mechanism including a cam and follower device, to rotate said shaft, to operate said roller into pressure engagement with and to retract it from said pad, respectively, during alternate half-turns of a full revolution of said device, second drive and operating mechanism, to rotate said roller, a reversible electric motor, multiple selective coupling means between said motor and said first and second mechanisms, to operate either of said mechanisms in dependence upon the sense of rotation of said motor, and electric circuit and control means for said motor operably connected with both said board and said support, to start said motor in a first direction and to operate said roller into pressure engagement with said pad by said first mechanism and to subsequently arrest and re-start said motor in the opposite direction, to rotate said roller by said second mechanism, by operation of said board from its normal position to and release from said control position.

13. In an ironing machine as claimed in claim 12, said board being provided with means to resiliently urge the same into said normal position, and additional control means to interrupt the motor operating circuit during the reverse motor operation by a further control position

of said board intermediate said normal and first control position.

14. In an ironing machine as claimed in claim 12, said board being provided with means to resiliently urge the same into said normal position and said circuit and control means being designed to start said motor by the establishment of a first operating circuit in a first direction upon operation of said board from its normal position to said control position, to continue rotation of said motor in said first direction upon initial displacement of said swiveling support and release of said board by the establishment of a second operating circuit, and to stop and restart said motor in the opposite direction by the establishment of a third operating circuit upon said roller reaching its operating engagement with said pad.

15. In an ironing machine, a stationary heating pad, an ironing roller, a support rotatively supporting said roller for cooperation with said pad, a rotatable guide board for feeding ironing material to said pad and roller and operable between a normal position and at least one control position, first drive and operating mechanism for said support including a cam and follower device, to operate said support into pressure engagement of said roller with and to retract it from said pad, respectively,

during alternate half-turns of a full revolution of said device, second drive and operating mechanism to rotate said roller, a reversible electric motor, multiple selective coupling means between said motor and said first and second mechanisms, to operate either of said mechanisms in dependence upon the sense of rotation of said motor, and electric circuit and control means for said motor operably connected with both said board and said support, to start said motor in a first direction and to operate said roller into pressure engagement with said pad by said first mechanism and to subsequently arrest and restart said motor in the opposite direction, to rotate said roller by said second mechanism, by operation of said board from its normal position to and release from said control position.
